UNITED STATES PATENT OFFICE.

WILLIAM DUNKERLEY, OF NORTH MELBOURNE, VICTORIA, AUSTRALIA.

REFRIGERATING SYSTEM.

Application filed April 13, 1927, Serial No. 183,540, and in Australia February 24, 1927.

- This invention relates to refrigerating systems and is applicable to such systems or installations operating either by compression or absorption.
- 5 The primary object of the invention is to provide improvements in refrigerating systems or installations whereby the normal cooling capacity of the system may be augmented to thereby enable a larger volume of work to be effected at the normal refrigerating temperature, or to lower the refrigerating temperature either uniformly throughout the system, or in any desired cooling zone or section thereof.
- 10 15 The foregoing object is attained by incorporating in the system a booster or auxiliary compressor of the rotary type whereby the gaseous cooling agent from the expansion or cooling coils of the system may, instead of passing directly through the main suction pipe to the means for putting it under higher pressure as is usual, be diverted through a by-pass or auxiliary circuit in which said auxiliary compressor is connected, and discharged from the latter into the main pressure-increasing means. In this manner, the normal suction pressure to which the gaseous cooling agent in any or all of the expansion coils or cooling sections of the system is subjected, may be supplemented by the suction developed in the auxiliary circuit, the resultant reduction in the suction pressure having the effect of intensifying the refrigerating action of the cooling agent.
- 20 25 30 35 40 45 50 55 The practical application of the invention to a refrigerating system permits of a greater output at the normal working temperature of the system, or alternatively the additional refrigerating effect due to the action of the auxiliary compressor may be concentrated in any desired cooling section or sections without affecting the temperature obtaining in the other section or sections. Thus a relatively low suction pressure may be maintained in any of the expansion coils or cooling sections without requiring such a low suction pressure throughout the system and thus calling for a main compressor of greater capacity and cost.
- 60 65 70 75 80 85 90 95 100 105 110 The auxiliary compressor may be readily incorporated in any existing refrigerating system without interfering with the latter except as may be required to connect piping which leads from the auxiliary compressor to the expansion coils or the main suction pipe of the system. Furthermore, owing to the low cost of the rotary auxiliary compressor, as compared with that of a reciprocating compressor, the benefits arising from the invention may be obtained with distinct economical advantages.
- Referring to the drawings which form part of this specification:—
- Fig. 1 is a diagrammatic view illustrating an application of the invention to a refrigerating system or installation of the compression type. The known or existing parts of the plan are indicated by relatively thin lines.
- Fig. 2 is a diagrammatic view illustrating a mode of applying the invention to a refrigerating system of the absorption type. The known or existing parts of the installation are indicated by relatively thin lines and the parts according to the invention by relatively thick lines.
- Fig. 3 is a longitudinal section of a preferred rotary auxiliary compressor employed in accordance with the invention.
- Fig. 4 is a cross section of the auxiliary compressor seen in Fig. 3.
- Fig. 5 is an enlarged detail view of portion of the auxiliary compressor seen in Figs. 3 and 4.
- The invention may be applied to a compression type refrigerating plant which, as indicated in Fig. 1 includes a reciprocating compressor 2, a main discharge pipe 3, a condenser 4, a condensed liquid pipe 6, one or more cooling or expansion coils 7, for each of which an expansion valve 8 is provided to control communication between the coil and the liquid pipe 6. Each expansion coil 7 communicates at its other end with a main suction or return pipe 9, through which the vaporized cooling agent passes on its way to the compressor 2. The above parts may be of any suitable construction and arranged and interconnected in any suitable manner. The plant may also include the usual oil and scale separators, an equalizer, a brine tank and various control and indicator devices, such parts being, however, omitted from the drawing for convenience of illustration.
- In accordance with this invention a booster or auxiliary compressor 11 may be disposed in any convenient position and adapted to be driven at the required speed. An auxiliary suction pipe 12, leads from an inlet port 13 (Fig. 4) of the auxiliary compressor, whilst an auxiliary discharge pipe 14 (Fig. 1) may lead from a header 16, having branches 17,

which communicate with outlet ports 18 (Figs. 4 and 5) of the auxiliary compressor 11, the latter being of the rotary type as previously mentioned.

If it is desired to extend the refrigerating effect of the plant, so that a larger amount of work may be carried out at the normal temperature or to lower the refrigerating temperature throughout the system, the outer ends of the auxiliary suction and discharge pipes 12 and 14 may be connected, as at 12^a and 14^a to the main suction pipe 9 at different points thereof, and a by-pass valve 19 interposed in said pipe 9 between its points of connection with the auxiliary pipes, as indicated by the thick unbroken lines in Fig. 1. By appropriate manipulation of said valve 19 direct communication between the main suction pipe 9 and the main compressor 2, may be cut off so that the gases from the expansion coils 7, instead of following their normal course, are diverted through the auxiliary suction pipe 12 into the auxiliary compressor 11 and pass therefrom through the auxiliary discharge pipe 14 into the main compressor 2. The path followed by the expanded gases, when the auxiliary compressor is connected in the system to operate in the manner previously described, is indicated by unbroken arrows in Fig. 1.

It will be evident that the additional suction to which the gases in the expansion coil or coils 7, may be subjected, by means of the auxiliary compressor 11, increases the refrigerating capacity of the plant and thus permits a greater output at the normal refrigerating temperature, or alternatively allows the plant to operate at a lower refrigerating temperature.

The auxiliary or by-pass circuit formed by the auxiliary pipes 12 and 14 and the auxiliary compressor 11, may be cut out by operating the by-pass valve 19 to thereby allow direct passage of gases through the main suction pipe 9, when it is desired that the plant should operate under normal conditions. Instead of connecting the auxiliary pipes 12 and 14 directly to the main suction pipe 9, as aforesaid, they may, if desired, be connected to the by-pass valve 19 which may be of any suitable internal construction.

If it is desired to lower the refrigerating temperature obtaining in any particular expansion coil or coils as 7^a, the outer ends of the auxiliary suction and discharge pipes may be connected, as at 12^b and 14^b directly to the particular expansion coil at points adjacent the outer end thereof, and a by-pass valve 19^b interposed in the outer end portion of the coil 7^a, between the points of connection of said auxiliary pipes and said coil, as shown in Fig. 1. In this case the gases from the expansion coil 7^a flow directly through the auxiliary suction pipe 12^b into the auxiliary compressor 11 from which they are dis-

charged by way of the auxiliary discharge pipe 14^b into the main suction pipe 9 and thence drawn into the main compressor 2, as indicated by the broken line arrows. The increased suction thus obtaining in the expansion coil 7^a lowers the temperature of that coil but does not in any way affect the normal refrigerating temperature of the other coils 7, from which the gases are induced along the main suction pipe 9 into the main compressor 2 in the usual manner. It will be evident that any of the expansion coils 7 may be operatively connected to, or placed into circuit with the auxiliary compressor 11 in the manner indicated, so that the gases are, on their way to the main compressor, by-passed through the auxiliary compressor 11 to thereby increase the suction and refrigerating effects of the respective coil or coils.

Referring now to Fig. 2 which indicates the application of the invention to a refrigerating system of the absorption type, the numeral 3 is employed to denote a main discharge pipe through which the cooling agent passes from a generator 31 to a condenser 4. The arrangement of the liquid supply pipe 6, expansion coils 7, and expansion valves 8, may be similar to that referred to in the compression type system, but the return pipe 9 of the absorption system communicates with an absorber 32. A pump indicated at 33 may be provided as usual to pump the relatively strong liquor from the absorber 32 by way of an exchanger or intercooler 34 into the generator 31, whilst piping 36 may be provided to conduct weak liquor from the generator to the absorber 32. The aforesaid parts may be arranged and connected in any suitable manner and other parts, such for example as an analyzer, rectifier, brine cooler, and various control and indicator devices may be appropriately incorporated in the system.

According to the invention the booster or rotary compressor 11 may be operatively connected between the return pipe 9 or the expansion coils 7, and the absorber 32 in a manner substantially similar to that described with reference to the compression type system. Accordingly, reference numerals, similar to those employed in Fig. 1 are utilized to indicate the auxiliary compressor 11, the auxiliary suction and discharge pipes and associated parts seen in Fig. 2. The operation of the booster or rotary compressor 11, seen in Fig. 2, is also substantially similar to that previously described but a brief description thereof will follow.

When the by-pass valve 19 as indicated by unbroken lines in Fig. 2 is closed to the return pipe 9 the gaseous cooling agent in the expansion coils 7 is subjected to the suction produced by the booster or rotary compressor 11, whereby the temperatures obtaining in the coils 7 may be uniformly lowered below normal, or if desired a greater volume of re-

frigeration may be effected at the normal working temperature. The gases are diverted through the auxiliary suction pipe 12 into the booster or compressor 11 and are expelled therefrom by way of the auxiliary discharge pipe 14 into the absorber 32 as indicated by unbroken arrows.

In instances where the rotary compressor 11 is directly connected to an expansion coil 7^a (or coils) as indicated at the right hand side of Fig. 2 the degree of suction obtaining within such coil and the resultant refrigerating effect may be increased without affecting the temperature of the other coil or coils. The path which the gases follow from an expansion coil 7^a, which is operatively connected or placed in direct circuit with the auxiliary compressor 11, is indicated by broken arrows in Fig. 2.

In all applications of the invention a stop valve 38 may be inserted in the auxiliary suction pipe 12 to enable the auxiliary compressor 11 to be positively cut out of the system should it be desired to make repairs or adjustment to the auxiliary compressor. Such valve 38 may be shut, when the aforesaid by-pass valve 19 is open to the main suction or return pipe 9 to thereby prevent gases from passing through the auxiliary suction pipe 12 into the rotary compressor 11.

As previously stated the auxiliary compressor 11 is of the rotary type and as seen in Figs. 3 to 5 may include the usual cylindrical casing 41, in which a rotor 42 is eccentrically mounted, the casing being provided with an inlet or suction port 13 for the low pressure gas and one or a series of outlet ports 18, controlled by suitable valve means 43, through which the gas is forced at relatively high pressure by way of branches or nipples 17 into a header 16 to which the aforesaid auxiliary discharge pipe 14 is connected. The rotor 42 may carry the usual spring influenced vanes 44 which contact with the inner surface of the casing 41.

In order to prevent the high pressure and high temperature gas in the discharge space 46 at one side of the rotor vanes 44 from leaking or escaping into the low pressure or suction space 47 at the other side of the rotor vanes, the casing 41, is preferably provided in accordance with the invention with a recess 48 which extends longitudinally of the casing 41 in its inner surface adjacent the outlet ports 18 and between the latter and the inlet port 13 and is adapted to accommodate a sealing strip 49. Extending from said recess 48 is one or a series of pockets or chambers 51 each of which is closed by a screw plug 52 or the like, and is placed into communication with the discharge or high pressure space 46 at one side of the rotor vanes 44, for example by means of an orifice or orifices 53 formed through the said sealing strip 49 whose inner surface may be cambered or bevelled as seen

in Fig. 5. The gas at high pressure being admitted into the said pockets or chambers 51 forces the sealing strip 49 tightly into contact with the outer periphery of the rotor 42 and the outer ends of the rotor vanes 44, as they arrive in alignment with the strip. The discharge or high pressure space 46 is thus effectively isolated from the suction or low pressure space 47. A spring 54 may be located in each pocket or chamber 51 between the screw plug 52 and the outer face of the sealing strip 49 to ensure that the latter is forced into leak proof contact with the rotor 41 and its vanes 44. The pressure exerted by the spring 54 may be adjusted as desired by means of the screw plug 52 which may have a lock nut 56 associated therewith.

It will be appreciated that the cost of a rotary compressor which is employed as an auxiliary to reduce the normal suction pressure in accordance with the invention, is considerably less than the cost of a corresponding reciprocating compressor of the type usually employed in refrigerating systems, and whilst rotary compressors are not ordinarily regarded as suitable for such work and owing to their relatively lower suction capacity would not be capable of satisfactorily supplanting or working independently of the reciprocating compressor in such installations the use of a rotary compressor in conjunction with the main reciprocating compressor or the absorber as hereinbefore described enables the capacity of a refrigerating system to be considerably increased at relatively low cost.

Having now described my invention what I claim as new and desire to secure by Letters Patent is:—

1. A refrigerating system comprising means for taking up refrigerant vapor and putting it under higher pressure, a condenser connected with said means, a high pressure conduit leading from the condenser, a return low pressure conduit leading back to said means, a plurality of expansion coils connected in parallel with said conduits, and a valve-controlled auxiliary circuit including a compressor and an auxiliary suction pipe and an auxiliary discharge pipe connecting said compressor with the main return pipe which leads from the expansion coil or coils to the first-mentioned means whereby the refrigerant vapor upon leaving said expansion coil may be caused to pass through said auxiliary pipe circuit before returning to said means.

2. A refrigerating system comprising means for taking up refrigerant vapor and putting it under higher pressure, a condenser connected with said means, a high pressure conduit leading from the condenser, a return low pressure conduit leading back to said means, a plurality of expansion coils connected in parallel with said conduits, and a

valve-controlled auxiliary circuit including in the main return pipe between the last-mentioned ends of the auxiliary suction and return pipes.

5. A refrigerating system comprising 30 means for taking up refrigerant vapor and putting it under higher pressure, a condenser connected with said means, a high pressure conduit leading from the condenser, a return 35 low pressure conduit leading back to said means, a plurality of expansion coils connected in parallel with said conduits, and a valve-controlled auxiliary circuit including a 40 compressor, auxiliary suction and discharge pipes extending between said suction or compressor and said main suction or return pipe to thereby provide for said refrigerant vapor an auxiliary circuit which leads from said main return pipe through the auxiliary suction pipe, the compressor and the auxiliary 45 discharge pipe back to said main return pipe, and valve means for controlling the passage of the vapor through said main return pipe and said auxiliary suction and discharge pipes, for the purpose specified. 50

3. A refrigerating system comprising means for taking up refrigerant vapor and putting it under higher pressure, a condenser connected with said means, a high pressure 15 conduit leading from the condenser, a return low pressure conduit leading back to said means, a plurality of expansion coils connected in parallel with said conduits, and a valve-controlled auxiliary circuit including 20 a compressor having an inlet port leading to a suction chamber and an outlet port leading from a discharge chamber thereof, auxiliary suction and discharge pipes connected at their one ends to said inlet and outlet ports 25 respectively and at their other ends to said main return pipe, and a by-pass valve located

4. A refrigerating system comprising 30 means for taking up refrigerant vapor and putting it under higher pressure, a condenser connected with said means, a high pressure conduit leading from the condenser, a return 35 low pressure conduit leading back to said means, a plurality of expansion coils connected in parallel with said conduits, and a valve-controlled auxiliary circuit including a 40 compressor, auxiliary suction and discharge pipes extending between said suction or compressor and said main suction or return pipe to thereby provide for said refrigerant vapor an auxiliary circuit which leads from said main return pipe through the auxiliary suction pipe, the compressor and the auxiliary 45 discharge pipe back to said main return pipe, and valve means for controlling the passage of the vapor through said main return pipe and said auxiliary suction and discharge pipes, for the purpose specified. 50

In testimony whereof I affix my signature.

WILLIAM DUNKERLEY
